METHOD AND APPARATUS FOR THE PRODUCTION OF MUSIC

Benjamin F. Messner, Millburn Township, N. J.

Application June 11, 1936, Serial No. 84,728

18 Claims. (Cl. 84—1)

This invention relates to the production of music from the mechanical vibrations of tuned vibrators, and more particularly to systems wherein said mechanical vibrations are translated into electric oscillations and these in turn into sound—
 i. e., wherein mechanico-electric and electro-acoustic translations are successively employed. This application is filed as a continuation in part of my co-pending application, Serial No. 705,888, filed January 9, 1934.

Such translations as above mentioned are broadly well known, as are also a variety of means and methods for effecting them. An object of this invention, however, is the provision of improved such translation means and methods.

According to one known mechanico-electric translation method which may be termed "electrostatic", the vibrations of the vibrators are caused to vary oscillatorily an electrical capacity, the capacity variations being employed in the production of the electric oscillations. A more specific object of my invention is the provision of improved electrostatic translation means and methods.

In instruments employing mechanico-electric translations there are frequently controlled qualitative characteristics of low frequency electric oscillations translated from the mechanical vibrations; this provides control of the output tone quality. An object of my invention is the provision in instruments of the class described of improved means and methods for controlling output tone quality. A more particular object of my invention is the provision of improved means and methods for controlling the timbre of the output tones.

Other objects are the provision of improved means and methods for amplifying the oscillations intermediately of the mechanico-electric and electro-acoustic translating; and the provision of a multi-vibrator musical instrument by which are produced electric oscillations adapted to be amplified and translated into sound by an amplifying and electro-acoustic translating system of well known and commonly available type.

Other and allied objects will more fully appear from the following description and the appended claims.

In the description reference is had to the accompanying drawings, of which:

Figure 1 is a view, partly perspective but principally diagrammatic, of a simple embodiment of my invention;

Figure 2 is a like view of a slightly more elaborate embodiment;

Figure 3 is a like view in greater detail of a particular embodiment; and

Figure 4 is a partly elevational and partly schematic view of another embodiment of my invention.

It is customary, in musical instruments involving mechanico-electric and electro-acoustic translation, to employ the mechanico-electric translating device or system to translate the vibrations of the vibrators directly into electric oscillations of the vibrational—i. e., low—frequencies. According to this invention, however, the mechanico-electric translating device or system is employed to translate the vibrations of the vibrators into electric oscillations having the form of a current of fixed high frequency modulated at the vibrational frequencies. The oscillations may be amplified at will while in this form; are thereafter demodulated or changed into the form of currents of the vibrational frequencies; and may then be further amplified at will and finally translated into sound.

This procedure has many advantages. A simple one is that the total amplification of the oscillations may be carried to greater degrees without elaborate amplifier stabilizing devices, since it is divided between amplifiers operating in different frequency ranges. Another is that the oscillations as first produced are suitable for application to the input of existing high-gain amplifying and electro-acoustic translating systems comprising in cascade a high frequency amplifier, demodulator, low frequency amplifier, and loud-speaker—i. e., the usual radio receiving set; this provides a significant economy. Still further advantages result from the procedure generally and from more particular features incident to its operation and structure, as hereinafter more fully appears.

In my invention the function of the translating apparatus is to modulate a current of fixed high frequency in accordance with the vibrations of the vibrators. In the illustrated embodiments of the invention the translating apparatus is of the electrostatic form above mentioned. In Figure 1 a simple embodiment is shown.

Herein appear strings 1, strung for example over triangular bars or bridges 2 between tuning- and hitch-pins not herein necessary to show. At least one of the bars 2 may be electrically conductive, whereby to connect the strings together and to further circuit portions as hereinafter set forth. In slight spaced relation to the several strings is shown an electrode—for example a narrow, electrically conductive strip 3, which may

conveniently be secured to the top edge of Bakelite or other insulating strip 4. It will be obvious that a small electrical capacity will exist between the electrode or strip 3 and the thereto adjacent portion of each string 1, and that the several such capacities are in parallel and thus form a total capacity from strip to strings; this total capacity may be designated as 5.

The capacity 5 is connected in series with the generator 6 of current of a fixed high frequency. This frequency is intended to be appreciably above the highest frequency to appear in the finally produced music, and is conveniently above the range of human audibility and permissibly of such high frequencies as are employed as carriers in radio transmission. A series circuit including the capacity 5 and generator 6 is completed through a device 7 responsive to current in the circuit. This for example may be a resistance, it being appreciated that the voltage thereacross will vary directly in accordance with the current therethrough.

The vibration of each string may be produced as by striking with a hammer 8; it will of course be complex—i. e., will occur at a particular fundamental frequency and harmonics thereof. Although the string is not relied on itself to produce sound, its vibrational components just mentioned are of frequencies intended to appear in the finally produced music—i. e., are of audible frequencies.

A normal value of high frequency current is of course caused by the generator 6 to flow in the circuit 5—6—7. Upon vibration of any of the strings 1 there will be oscillatorily varied the capacity 5 and hence its reactance and the impedance of the circuit 5—6—7. This variation of impedance may be either substantially linear with respect to the vibration of the portion of the vibrating string adjacent to strip 3, or non-linear with respect thereto, depending on the relations between string-to-strip spacings, string vibration amplitudes, etc., and tending particularly with spacings of the order of peak vibration amplitude to non-linearity. To the extent of the non-linearity it will be understood that the impedance value will vary not only at such frequencies as may be present in the string portion vibration, but also at multiples thereof, which will be understood to be harmonically related to the fundamental vibrational frequency of the string. Obviously the high frequency current in the circuit will be alternately increased and decreased, or in other words modulated, at the frequencies of impedance variation of the circuit.

The degree or percentage of modulation will obviously vary with string vibration amplitude. It will also depend on the ratio of average reactance of the capacity 5 to the average total impedance of the circuit 5—6—7, being greater the greater is this ratio. The degree or percentage of modulation will further depend on the relation of the actually varied portion of the capacity 5 to the total capacity, being obviously less the greater is the number of strings 1. In the usual case even with high string vibration amplitudes the percentage modulation is relatively low; under these conditions the modulation is substantially linear with respect to the impedance variation, and hence in general bears substantially the same relation to string vibration as does the impedance variation.

The modulated high frequency current flowing through the resistance 7 will obviously produce a similarly modulated high frequency voltage

thereacross. Typical further portions of a complete music-producing instrument or system may be connected as by leads 27 across this resistance. Thus there are shown in Figure 1, in cascade, high frequency amplifier 18, potentiometer 19, demodulator 20, potentiometer 21, low frequency amplifier 22, and loudspeaker 23. The modulated high frequency voltage appearing across the resistance 7 is amplified by amplifier 18, controlled in respect of amplitude by potentiometer 19, and demodulated by demodulator 20 to produce oscillations of the original vibrational fundamental and harmonic frequencies. These oscillations may be controlled in respect of amplitude by potentiometer 21, amplified by 15 amplifier 22, and translated into sound by loudspeaker 23.

It is convenient to think of the modulating action of the capacity 5 as the addition, to a steady high frequency current passing therethrough, of side-bands—i. e., of currents having frequencies which are the sums and differences of the fixed high frequency and the several component frequencies of impedance variation. A pair of side-bands—i. e., one "sum" or upper and one "difference" or lower side-band—will be produced by each different frequency impedance variation component. The term "side-frequency current" is conveniently used hereinafter to denote one complete such pair of side-bands, each 30 side-frequency current therefore being actually a current of dual frequency. Upon demodulation each different side-frequency current of course produces a different low frequency current, these low frequency currents corresponding in frequency to the original impedance variation components.

Control of the general amplitude of the modulated high frequency current—i. e., of both side-frequency currents and current of fixed 40 high frequency, as by potentiometer 19—or control of the degree of modulation—i. e., of the general amplitude ratio of side-frequency currents to current of fixed high frequency—may be employed to effect control of output volume 45 from loudspeaker 23. Such control may be considered purely quantitative; it affects only the volume of the output sound. There is also possible, however, qualitative control of the modulated high frequency current, for the control of 50 output tone quality.

For example, if there be controlled the relative amplitudes of the several side-frequency currents produced by vibration of any single string 1 and the resulting impedance variations, there will be controlled the relative amplitudes of the individual low frequency currents which are produced upon demodulation and whose frequencies respectively correspond to those of the impedance variation components; this will result in 55 control of timbre of the output tone. Thus considering the impedance variation occasioned by vibration of any string 1 as comprising a first component identical in frequency with the fundamental frequency of the string, a second 60 component of twice that frequency, a third of three times that frequency, and so on, the corresponding side-frequency currents may respectively be termed first, second, third, etc., and the presently discussed control is intended to vary 65 70 at will the amplitude relationships between these side-frequency currents.

In providing this control I may employ, for fundamental frequency (e. g., for each string or other vibrator of a multi-vibrator instrument), 75

a plurality of capacities arranged for oscillatory or vibratory variation with a common fundamental frequency but in mutually distinct manners. Occurrence in such different manners may, for example, be occurrence with distinct harmonic structures and/or waveforms; and a plurality of capacities arranged for variation with common fundamental frequency but obviously distinct harmonic structures and waveforms have been shown in Figure 2. Herein appear two capacities 5' and 5'' respectively formed by a portion of each string with conductive strip 3', and by a distinct portion of each string with conductive strip 3''; the vibratory variations of capacities 5' and 5'' will be of different waveform because these capacities are formed with respectively different portions of each string, of which the vibrational harmonic structure and waveform is well known to vary along its length. Respectively in series with the capacities 5' and 5'' I may employ the generators 6' and 6'' generating currents of identical fixed high frequency; and a single resistance 7 may complete the series circuit for 5'-6' and the series circuit for 5''-6'', the voltage appearing across resistance 7 being applied as in Figure 1 to succeeding portions of the circuit.

The identity of the fundamental frequencies of the variations of capacities 5' and 5'' results in the production by these capacities of two similarly ordered series or groups of side-frequency currents, while the dissimilarity of waveform of the variations results in different amplitude (or amplitude and phase) relations between corresponding side-frequency currents in the two groups. It will further be appreciated that the two groups of side-frequency currents join in resistance 7 to form a final combination. In this final combination the first side-frequency current will be algebraic sum of the first side-frequency currents in the two groups; the second side-frequency current will be algebraic sum of the second side-frequency currents in the two groups, etc. If the amplitude and/or phase of the composite group of side-frequency currents produced by one of the capacities 5' and 5'' be varied—or in other words if the relative amplitudes and/or phases of the two groups of side-frequency currents be varied—the relative amplitudes of the several side-frequency currents in the final combination will be varied.

I may vary the relative amplitudes and phases of the side-frequency currents produced by the two capacities 5' and 5'' by varying the relative amplitudes and phases of the fixed high frequency currents passing therethrough, it being well understood that the amplitude and phase of any side-band for given modulation follow those of the current being modulated. Thus in Figure 2 the arrow through each of the generators 6' and 6'' denotes variability of amplitude and phase.

The oscillatory variations of a plurality of capacities, each caused by a respective complex vibration, may occur in mutually distinct manners, although in the respective vibrations the harmonic structures are identical and the vibrational waveforms similar except for mutual inversion or phase displacement. The oscillations produced by capacities varying in manners which are distinguished from each other only by such vibration phase displacement or inversion are yet adapted for combination to produce a variety of tonal effects, in view of nonlinearities of capacity and impedance variations with the vibra-

tions. In Figure 4 I have shown for each vibrator two capacities varied by vibrations of similar harmonic composition but of mutually inverted waveforms—as well as a third capacity arranged for variation with a distinct harmonic structure and waveform—and the modulation of currents of a common fixed high frequency in these three capacities.

This illustration has been presented by way of example with vibrators consisting of tuned free reeds 101, each shown in cross-section terminally secured to a respective suitable apertured reed-block 102 and adapted for selective vibration by an individual flow of air in well known manner; this vibration of each reed will be understood to be in general greatest at the free reed extremity 101a, and, as illustrated, to take place in an up-and-down direction. Above each reed, preferably near its free extremity, may be adjustably secured an electrode or screw 103', as in the stationary insulating block 104'; and below the reed, for example opposite the electrode 103', may be similarly secured in stationary insulating block 104'' another electrode 103''. Each of these electrodes will of course be so adjusted as not to be touched by the reed in its vibration, but may typically be adjusted to meet this specification with only a small safety factor. There may also be provided for each vibrator a third electrode 103''', for example in very slight spaced relationship to the free end of the reed and most closely approached by the reed at some intermediate point in its vibrational swing—e. g., at the rest position of the reed. The several vibrators may be mutually connected; corresponding electrodes for the several reeds may be mutually connected; and the parallel capacities of vibrators to top electrodes 103' may be considered as a single capacity 105', the paralleled capacities of vibrators to bottom electrodes 103'' as a single capacity 105'', and the paralleled capacities of vibrators to end electrodes 103''' as a single capacity 105'''. In series with each of these three capacities 105', 105'', and 105''' may be connected a respective one of the generators 6', 6'' and 6''' of common fixed high frequency oscillations, but of independently variable amplitude and phase; and, as in Figure 2, a single common impedance or resistance 7 may complete the three series circuits thus formed.

It is readily seen that the inherently complex vibration of any of the reeds oppositely affects the capacities 105' and 105'', so that each capacity is actually varied by a respective complex vibration having a waveform inverted from that of the vibration varying the other capacity. Accordingly, in view of non-linearities hereinabove mentioned, the capacities 105' and 105'' produce distinct oscillatory impedance variations, and accordingly different composite groups of side-frequency currents in the high frequency oscillations passing therethrough. By the variability of the amplitude and phase of the outputs of the generators, 6' and 6'' as in Figure 2, there may be combined in the impedance 7 a wide variety of final side-frequency current groupings. This variety may of course be further widened by the employment of the illustrated capacities 105'''; each of these will be increased to a maximum twice per fundamental cycle by the then passage of its reed closest to the associated electrode 103''' and will therefore have small fundamental and large double-frequency components, obviously producing a thoroughly distinct composite group of side-frequency components for regu- 75

lable combination with those from capacities 105' and 105'', above discussed.

Figures 2 and 4 are of course relatively schematic; a more specific embodiment of the system of Figure 2, for example, appears as Figure 3. In this figure the generators 6' and 6'' of Figure 2 appear as the coils 11' and 11'', each variably coupled to the fixed coil 10 and this in turn supplied with current of fixed high frequency by connection thereof through potentiometer 28 to the output of amplifier 16, of which the input is connected to a source 15 of current of such frequency. Preferably the coupling coefficient of each of the coils 11' and 11'' to the coil 10 is variable from a given positive value through zero to a like negative value, as by rotation of the coil about an associated pivot 17, so that any voltage within a range of amplitudes and in either of two phases may be induced in either coil 11' and 11''. There is included in Figure 3 a third coil 11''' similar to coils 11' and 11'', and a third capacity 5''' formed by a conductive strip 3''' with the strings; this, as did Figure 4, illustrates the contemplation by my invention of a larger number of translating devices than two, it being obvious that the principles of operation are applicable to any number of translating devices. Shielding schematically shown as 30 may be disposed about the source 15, coils 10, 11', 11'' and 11''', resistance 7 and at least partially about the strips 3', 3'' and 3''', for the reduction of sensitivity of the system to stray electrostatic fields; this shielding may be established for example at the potential of strings 1.

It is to be observed that the variation in the phases and amplitudes of side-frequency currents produced by each of the capacities 5', 5'', 5''' is effected by, and therefore necessarily accompanied by, a like variation of the high frequency current flowing through each of the capacities. Thus under certain conditions of adjustment the steady high frequency current through the several capacities may be of low or zero algebraic total in the resistance 7; then the oscillations of fixed high frequency applied to the demodulator later in the circuit would be low or zero, although the side-frequency oscillations were of finite amplitudes. Under these conditions the demodulator would not function properly, it being well recognized that both the fixed high frequency oscillations and side-frequency oscillations are required for proper demodulation. In order to overcome this difficulty I may abstract an unmodulated voltage of the fixed high frequency from the generating system and add it to the voltage which appears across the resistance 7 and which is fed to the demodulator. Such a voltage may be obtained from a coil shown in Figure 3 as coil 24, coupled to the coil 10, and connected in series with one of the leads 27. In order that this voltage may always be made to increase and not further to decrease the steady high frequency voltage appearing across resistance 7 I may make the coupling of the coil 24 to coil 10 variable, as is the coupling of each of the coils 11', 11'', 11''', so that phase may be reversed, as well as amplitude controlled, at will.

Instead of relying on frequent adjustments of coil 24, however, I prefer to arrange the circuit so that the unmodulated voltage under discussion will be positively maintained in a phase somewhere near 90 degrees removed, either forward or backward, from the phase of the steady high frequency voltage across resistance 7. This

is readily accomplished by inserting an inductance coil 25 in series with coil 24, and a resistance 26 across both coil 24 and inductance 25, so apportioning the ratio of absolute reactance value of inductance 25 (at the fixed high frequency) to the value of resistance 26 as to satisfy the desired phase conditions. Thus letting R represent the normal value of resistance 7 and X the absolute reactance value of all the capacities 5', 5'' and 5''' considered in parallel, the 10 mentioned ratio should be fixed at R/X .

In Figure 3 the leads 27 are shown connected to the input circuit of a thermionic amplifying tube 18a, which is analogous to a portion of the high frequency amplifier 18 in Figure 1. The cathode 15 of this tube may be heated by any suitable means, not shown; its grid may be biased negatively with respect to the cathode as by battery 31; and its anode current may be supplied as by battery 32. The current transmitted from tube 18a to further circuit portions need of course comprise only frequencies lying in the band between the fixed high frequency less the highest modulating frequency and the fixed high frequency plus the highest modulating frequency. For highest transmission efficiency within this band the output circuit of the tube 18a may be tuned, as by the capacity 33 and inductance 34.

Figure 3 illustrates the principal high frequency amplification, the demodulation, and the low frequency amplification as performed by a radio receiver 29, to the output of which is connected or in which is included the loudspeaker 23. The input of the receiver 29 is connected through the leads 35, which may be shielded as by an extension 36' of the shielding 30, to the coil 36 coupled to the inductance 34. The radio receiver is, of course, to be tuned to the fixed high frequency, which is therefore chosen to be within its tuning range. The volume control or controls of the radio receiver 29—analogous to 19 and 21 of Figure 1—may of course be employed to control the level of output sound from loudspeaker 23.

It may be more convenient, however, to control this output sound level in other portions of the system. In the ordinary case this may be done by varying the amplitude of the side-frequency currents and preferably of the current of fixed high frequency as well; this may be done by adjustment of potentiometer 28. In the special case, however, in which the radio receiver 29 is of the type which automatically reduces the amplifying action of its high frequency amplifying portion as the amplitude of oscillations there-through increases, there will be found generally ineffective an attempted control of output volume level in the manner just outlined as preferred for the simple case. In this special case, control of output volume by adjustments of system portions preceding the receiver 29 may be effected by control of the effective percentage modulation as seen by the receiver. A specific manner of effecting such control is to vary the fixed high frequency oscillation amplitude at the tube 18a without change of amplitude of the side-frequency oscillations; this may be done as by adjustment of the coupling of coil 24 to coil 10. It is to be noted that increase of this fixed high frequency oscillation amplitude will decrease the output volume, and vice versa.

Control of qualitative characteristics of the modulated current is not limited to variation of relative amplitudes of the several side-frequency currents therein for timbre control purposes. In

various United States Letters Patent heretofore issued to me—i. e., No. 1,912,293, May 30, 1933; No. 1,915,858, June 27, 1933; No. 1,933,295, October 31, 1933; and No. 1,933,298, October 31, 1933—
 5 I have shown various special arrangements of vibrators and of translating devices with respect thereto, for the control of the successive instantaneous amplitudes, or dynamic characteristics, of the output tones. It will be obvious that the 10 translating devices, when employed according to the instant invention for the modulation of a fixed high frequency instead of the direct production of a low frequency current, are still entirely susceptible of arrangement in the manners disclosed in those patents for the production of effects similar to those set forth herein.

The regulable translation from a vibrator by means of a plurality of devices (e. g., electrodes) arranged in association with substantially a single portion of the vibrator (e. g., arranged above and below, and if desired opposite, a single reed portion) is not in itself broadly claimed herein; broad claims thereto have been made in my co-pending application #758,155, filed December 14, 25 1934.

While I have disclosed my invention in terms of particular embodiments thereof, it will be understood that these embodiments are illustrative rather than comprehensive, and that the scope 30 of my invention is intended to be expressed in the following claims.

I claim:—

1. In a musical instrument, the combination of a tuned vibrator; a source of high frequency electric oscillations; and a mechano-electric translating device and means for supplying said oscillations thereto, said device being associated with said vibrator and being adapted to modulate said oscillations in accordance with the vibrations of said vibrator.

2. The combination claimed in claim 1, further including means for adding to said modulated oscillations unmodulated oscillations of said high frequency, and means for controlling the amplitude of said added oscillations.

3. The combination claimed in claim 1, further including means for adding to said modulated oscillations unmodulated oscillations of said high frequency, and means for displacing the phase of said added oscillations.

4. In a musical instrument, the combination of a tuned vibrator; a conductive element in spaced relation thereto and forming therewith an electrical capacity adapted to be oscillatorily varied by the vibration of said vibrator; and a circuit serially including a source of high frequency oscillations, a current-responsive device, and said capacity.

5. In a musical instrument, the combination of a tuned vibrator; a source of high frequency electric oscillations; mechano-electric translating means and means for supplying said oscillations thereto, said translating means being associated with said vibrator and being adapted to modulate said oscillations in accordance with the vibrations of said vibrator; and means for controlling qualitative characteristics of the modulated oscillations.

6. In a musical instrument, the combination of a tuned vibrator whose vibration includes a plurality of harmonically related audible frequency components; a source of high frequency oscillations; mechano-electric translating means and means for supplying said oscillations thereto, said translating means being associated

with said vibrator and being adapted to modulate said oscillations in accordance with the vibrations of said vibrator whereby said oscillations are caused to include side-frequency components respectively corresponding to said vibration components; and means for controlling the relationships between the several side-frequency components of the modulated oscillations.

7. In a musical instrument, the combination of a tuned vibrator; a plurality of mechano-electric translating devices and means for supplying thereto respectively a plurality of currents of a common high frequency, said devices being variously associated with said vibrator whereby to modulate said currents in respectively different manners; and means connected with said translating devices for combining the modulated currents therefrom to produce a composite modulated current.

8. The combination claimed in claim 7, further including means associated with said supplying means for varying the relationships between the several said currents.

9. The combination claimed in claim 7, further including means for varying the relationships between the several said currents.

10. The combination claimed in claim 7, further including means for adding to said composite current an unmodulated current of said high frequency.

11. The combination claimed in claim 7, further including means for adding to said composite current an unmodulated current of said high frequency, and means for displacing the phase of said added current.

12. In a musical instrument, the combination of a tuned vibrator; a plurality of electrodes variously associated with said vibrator in spaced relation thereto and forming therewith electrical capacities adapted to be oscillatorily varied in respectively different manners by the vibration of said vibrator; means for passing a plurality of currents of a common high frequency through said capacities respectively, whereby to modulate said currents; and means connected with said capacities for combining said modulated currents.

13. In a musical instrument, the combination of a tuned vibrator different portions of which vibrate at the same fundamental frequency but with respectively different waveforms; a plurality of mechano-electric translating devices and means for supplying thereto respectively a plurality of currents of a common high frequency, said devices being associated with respectively different portions of said vibrator, and respectively adapted to modulate said currents in accordance with the vibrations of the therewith associated vibrator portions; and means connected with the several said translating devices for combining the modulated currents therefrom to produce a composite modulated current.

14. In a musical instrument, the combination of a tuned vibrator different portions of which vibrate at the same fundamental frequency but with different waveforms; a plurality of mechano-electric translating devices variously associated with said vibrator and arranged to modulate in respectively different manners high frequency oscillations thereto supplied; a source of oscillations of fixed high frequency; a plurality of coils coupled to said source, the coupling thereto of at least one of said coils being variable; a plurality of circuits, each including a respective one of said coils and a respective one of said

translating devices; and a common current responsive means connected with all of said circuits.

15. A musical instrument having output terminals adapted for connection to the input of a radio receiver, comprising in combination a plurality of tuned vibrators and means selective with respect thereto for vibrating the same; a mechano-electric translating system and means 10 for supplying thereto electric oscillations of high frequency, said system being associated with said vibrators and adapted to modulate said high frequency oscillations in accordance with the vibrations thereof; and means connected with said 15 translating system for supplying modulated oscillations therefrom to said output terminals.

16. The instrument claimed in claim 15, further including adjustable means for supplying to said output terminals unmodulated oscillations 20 of said high frequency, whereby the effective degree of modulation of said modulated oscillations may be controlled.

17. A musical instrument having output terminals adapted for connection to the input of a radio receiver, comprising in combination a 25 plurality of tuned vibrators and means selective with respect thereto for vibrating the same; a plurality of mechano-electric translating sys-

tems and means for supplying thereto respectively a plurality of currents of a common high frequency, said systems being variously associated with each of said vibrators, and adapted to modulate said high frequency currents in respectively different manners; means for controlling the relationship between the currents modulated by the several said translating systems; and means for supplying to said output terminals the several said modulated currents.

18. The method of producing a musical tone of given fundamental frequency and of varying its timbre, which includes producing in each of a plurality of currents of common high frequency a complex modulation whose components are of 15 the given frequency and harmonics thereof, the inter-component amplitude ratios in the modulations of the several said currents being respectively different; controlling the relationships between the several said modulated currents; combining the several said modulated currents to produce a composite modulated current; demodulating said composite current, whereby to produce a complex current of the given frequency and harmonics thereof; and translating said last 20 mentioned complex current into sound.

BENJAMIN F. MIESSNER.
